Patented July 7, 1942

Des. 132,979

UNITED STATES PATENT OFFICE

132,979

DESIGN FOR A COSMETIC CONTAINER

Peter Christian Nelson, Burbank, Calif.

Application December 12, 1941, Serial No. 104,599

Term of patent 3½ years

To all whom it may concern:

Be it known that I, Peter Christian Nelson, a citizen of the United States, residing at Burbank, in the county of Los Angeles and State of California, have invented a new, original, and ornamental Design for a Cosmetic Container, of which the following is a specification, reference being had to the accompanying drawing, forming part thereof;

The figure is a perspective view of a cosmetic container, showing my new design.

I claim:

The ornamental design for a cosmetic container, as shown.

PETER CHRISTIAN NELSON.
